UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

UPPER-SHAPING MACHINE.

1,361,960.

Specification of Letters Patent.

Patented Dec. 14, 1920.

Application filed June 4, 1917. Serial No. 172,683.

To all whom it may concern:

Be it known that I, MATTHIAS BROCK, a citizen of the United States, residing at Boston, in the county of Suffolk and State 5 of Massachusetts, have invented certain Improvements in Upper-Shaping Machines, of which the following description, in connection with the accompanying drawings, is a specification, like reference characters on 10 the drawings indicating like parts in the several figures.

This invention relates to machines for shaping upper materials and is herein shown as embodied in a machine which is 15 adapted for molding the heel portions of shoe uppers, the characteristic features of the type of machine illustrated being more fully described in prior United States Letters Patent Nos. 1,197,437 and 1,197,439, 20 granted Sept. 5, 1916 upon applications filed by me.

One object of this invention is to produce more effective shaping and better distribution of the fullness in the margin of an 25 upper that is forced inwardly over a convex end portion of a shoe last or form by relative movement between the form and margin engaging means. The most satisfactory means for forming the margin of the upper 30 into an inwardly turned sole attaching flange comprises end embracing wipers which gather and wipe the margin inwardly over the tread face of the form or last. The inturned margin resolves itself into plaits 35 or folds to take care of the fullness caused by bending it into a smaller circle or curvature. A feature of this invention consists in a novel construction and arrangement of means to coöperate with flange shaping 40 means to distribute the fullness so that large plaits are avoided. This is effected in the construction herein shown by confining the margin of the upper against the edge 45 of the wipers as they advance and close so as to restrain the marginal stock from doubling on itself to produce folds, the 50 illustrative construction comprising means to engage the inner side of the upstanding margin of the upper around the shoe end and hold it in upstanding position and 55 against the wiper edges while the wipers close over the shoe end. The margin is thereby prevented from wrinkling while it is held upstanding and is progressively

drawn down between the wiper edges and 55 the holding means to produce the inturned flange. An effective embodiment of this feature of the invention consists in the combination with a form and means to bend the margin of the work inwardly over the form, 60 of margin holding means guided on the form. The holding means may be advantageously spring held in its operative position and movable by force transmitted from the wipers. 65

Another feature of the invention consists in the provision of means for preventing displacement of the flange by the margin holding means, for example, during the return movement of the wipers or other bending means over the flange. In the illustrative machine the wipers are reciprocated repeatedly and the margin holding means is organized to operate during the first closing movement of the wipers and to remain inoperative during subsequent reciprocations of the wipers over the same piece of work. 75

A further feature of the invention consists in a novel construction and arrangement of upper shaping means designed to 80 prevent displacement of the upper in the upper shaping operation. The illustrative construction embodying this feature comprises inside margin holding means which is arranged to project beyond the edge of the 85 bottom face of the inside form in position substantially to engage the upper stock in the position which it occupies before the shaping operation begins. The margin of the upper is thus gripped between the holding means and the wipers at the beginning 90 of the upper shaping operation, in time to restrain the upper as a whole from tipping movement relatively to the form in such manner as to depress unduly the portions at 95 the sides of the form including, for example, the wings of the counter.

In the operation of a machine constructed in accordance with the preferred embodiment of this invention there is a marked 100 tendency to reduce the extent of fullness to be distributed in the overwiped margin. This is due to the stretching action on the margin of the stock widthwise from the edge of the form or last and its consequent lengthwise contraction as it is drawn out and turned down, so that fewer plaits are required. 105

In addition to the foregoing the invention includes various features of construction and combinations of parts designed with a view to the application of the invention to upper shaping mechanisms of the type shown in said prior patents and particularly to automatic machines embodying the invention set forth in said Patent 1,197,439. These features will all be more fully understood from the following description with the aid of accompanying drawings of an illustrative machine embodying the invention, and will then be particularly pointed out in the claims.

Figure 1 of the drawings is a side elevation of a machine embodying the present invention;

Fig. 2 is a perspective view dealing particularly with parts of the machine added by this invention;

Fig. 3 is a perspective view showing the upper shaping devices at the beginning of their action on an upstanding margin of an upper which is to be shaped into an in-turned upper attaching flange over the tread face of a heel form;

Fig. 4 is a similar view showing the conditions as the operation proceeds with the margin maintained upstanding while it is being inturned;

Fig. 5 is a plan view of end embracing wiper mechanism such as shown in the patents hereinbefore referred to and the co-operating margin holding means approximately in the relation shown in Fig. 3;

Fig. 6 is a similar view after the wipers have completed a flange forming movement inwardly over the work, forcing the margin holding means ahead of them;

Fig. 7 is a vertical longitudinal section through the margin holding means and the upper part of the form.

Figs. 8 and 9 show modifications.

As pointed out in the said patents, the machine comprises a plurality of duplicate units built into one machine so that a plurality of shoe uppers may be in process at the same time. It will suffice to describe this invention in connection with one of said units.

The upper shaping mechanism comprises a last or form 2, herein shown as a metal heel form of more pronounced curvatures than the corresponding last; a multi-part form embracing mold 4 shown in dotted lines in Fig. 1 and backwardly into which the form carries the work; and heel embracing wipers shown best in Figs. 5 and 6 and comprising advancing and closing end members 5 and side members 6 that have a closing movement without advancing.

The machine is power driven, being controlled by a foot treadle 10 connected with a clutch 12 on a driving shaft 13. This shaft is geared to the cam shaft 14 which

operates through a lever 15, a rod 16 and form carrier 18 to draw the form back into the mold; through a lever 20 and toggle 22 to close the mold for clamping the upper about the side faces of the form; through a lever 24 and rod 25 to close the wiper controlling clutch and set the wipers to reciprocating; and through a lever 26, toggle 27 and rods 30, 32 and spring 33 to raise the form yieldingly against the wipers. These movements having been effected, the cam shaft comes automatically to rest while the wipers, which are driven from a constantly running pulley 35, are continued in reciprocation to shape the inturned flange of the upper by repeated rubbing movements forth and back over the flange.

The mechanism and organization thus far described is like that more fully shown and described in said prior patents and the present invention is not concerned with the details thereof.

The top face of the form 2 is dove-tailed to provide a slideway for the foot piece 40 of the margin holding means. In the foot piece is guided, the side rod or stem 42 to the head of which are secured toggle members or links 44. These are pivotally connected to the front or free ends of the margin holding members 45 which are pivotally connected together and to the foot piece 40 as shown in Fig. 7 and are shaped to conform substantially to the curvature of the convex rear edge of the form 2. The margin holding members are maintained normally in the outspread position shown in Figs. 2, 3 and 5 by the assistance of light leaf springs 46 secured to the foot piece 40 and extending between the free ends of the members 45.

The margin holding means is maintained in the position shown in the slideway on form 2 by a presser 50 which is the upper arm of a bell-crank lever fulcrumed in the form carrier 18 and having a horizontal arm 52 pressed down upon by a spring 54, Fig. 2. The spring 54 allows the margin holding members to be pressed forwardly and swung inwardly against a substantial yielding resistance as the wipers advance and close.

The construction and organization thus far described is such that the margin holding members stand in the position shown in Figs. 1, 2 and 3 when the form 2 is in work receiving position. At such time they may serve as a height gage to guide the operator in positioning the work at the right elevation to provide the desired width of inturned flange on the upper. The margin holding means moves backwardly with the form as the latter carries the work into the mold, see Fig. 5. As the wipers advance the members 45 hold the margin in upstanding position around the convex portion of the edge of

the form and cause the upper to be gripped or pinched against their outer faces. During the further advance and closing of the wipers, see Fig. 4, the members 45 continue 5 to hold the margin in upstanding position free from any concentration of fullness into folds or plaits and require the margin to be stripped under tension from between said members 45 and the wipers. The spring 54 is preferably strong enough to prevent the 10 passage of any folds or doubled portions of the stock between the members 45 and the wiper edges, with the result that the fullness is ironed out and the margin stretched 15 widthwise and therefore contracted lengthwise. As the advance of the wipers proceeds the condition shown in Fig. 6 is reached where the margin has been pulled down entirely under the wipers. 20 It is desirable that the members 45 shall not follow the wipers in their backward stroke from the position shown in Fig. 6 because there would be a tendency to disturb the wiped down flange. To control the margin holding means in this respect the arm 52 in the construction shown in Figs. 1 and 2 carries a spring pin 55 having a beveled 25 outer end which engages under a stationary roll 56 when the form carrier 18 thrusts the 30 form back into the mold. When the wipers advance and move the members 45 and the presser 50 forward the arm 52 is raised against resistance of spring 54, the beveled end of the spring pin 55 permitting it to 35 clear the roll 56 and the spring back of the pin projecting the pin into position to rest upon the roll 56, which thereafter will hold the presser from returning the margin holding means to starting position. This not 40 only relieves the members 45 from pressure tending to move them reversely lengthwise of the form, but also insures against their return movement laterally of the form in such manner as to displace the wiped-down 45 flange of the upper, the tension of the light springs 46 being insufficient to swing these members outwardly to the edge of the form as the wipers are backed away. The wipers may then reciprocate repeatedly over the 50 work while the margin holding means remains idle substantially in the position shown in Fig. 6.

In the illustrated machine the wipers are reciprocated repeatedly. When the operator, after having dealt with the work on the other units of the machine, is ready to remove the upper from the form 2, he starts the cam shaft by depressing the treadle 10 and the several parts are restored to starting 55 position, Fig. 1, the shoe being released with the heel portion of its upper shaped to fit a last and its margin formed into an inturned sole attaching flange. As the form carrier moves out to shoe discharging position, Fig. 60 1, the spring pin 55 is drawn off from the roll 56, thereby freeing the spring 54 to operate for returning the margin holding means to work gaging position, maintaining it there during the application of the next shoe upper and in margin holding relation 70 to the wipers during their flange forming advance over said next upper. It will be noted that the pin 55 is released from the roll 56 before the form 2 reaches its outermost position. This release and the consequent actuation of the margin holding means 75 rearwardly over the form 2 by the spring 54 is utilized to overcome adhesion of the upper to the form and facilitate removal of the work from the form by the operator. 80

In Figs. 8 and 9 is shown a modification characterized by a new position, and combinative effect, of the margin holding means relative to other parts operating on the work, and by an alternative controlling mechanism 85 for the margin holding means. In this embodiment of the invention the margin holding means is so constructed and arranged relatively to a form 2 having a vertically convex rear face that in the normal 90 work receiving position of the parts the stock engaging outer edge face of said means is substantially in vertical alignment with the outermost part of said convex face of the form around the curved rear end of the 95 form.

It will be noted by reference to Fig. 1 that in the construction there shown the margin holding means is arranged to have a work receiving position substantially at the edge 100 of the heel seat face of the form. This is the right condition for molding uppers that have been cut to shape at the back seam, that is, are formed with a pocket as shown for example in application United States Letters Patent No. 1,238,856, granted Sept. 4, 105 1917, on application of Thomas F. Whelan.

In dealing with work in which the upper has not been cut to approximate the shape of the rear end of a convexly faced mold or 110 in which a straight or unmolded counter is included with the upper materials, there is a tendency for the flange bending wipers 5 to tip the upper about the rear end face of the form 2 and thus move the stock downward with relation to the front portion of the mold. This throws the wings of the counter down and provides insufficient width 115 of margin to bend in for producing the sole attaching flange. It also tends to produce 120 excess fullness at the top of the heel, which causes the shoe to fit imperfectly. These difficulties are overcome by the construction and arrangement shown in Figs. 8 and 9 for presenting a margin holding face on members 45 in coöperative relation with the margin bending wiper members 5 in a position in which said face is substantially aligned vertically with the extreme rear part of the form 2. As thus arranged the members 125 45 130

and the wipers 5 grip the upstanding margin of the shoe stock round the rear end of the form and for a short distance along the sides of the form before the stock can be tipped about the rear end of the form and thus restrain the portions of the stock that extend forwardly along the sides of the form from downward displacement while the stock is being shaped, either to the rear end 10 face of the form by the molds 4 or to produce the sole attaching flange by the wipers 5 and 6.

In Fig. 8 the latching means of Fig. 1 including the spring pin in the end of arm 52 is replaced by a pivoted spring pressed latch 60 which is tipped toward the right by said arm as the arm travels in that direction with the form carrier 18, and when the arm is lifted, by the forward displacement of the 15 margin holding means and its presser 50, the end of arm 52 rides up the edge of the latch until it seats in the recessed portion of the latch which holds it up and prevents the return of the arm and the margin holding 20 members 45 by spring 54 when the wipers are retracted and during the successive subsequent reciprocations of the wipers until the form carrier is again moved toward shoe 25 discharging position when the end of arm 52 is drawn forwardly out of the recessed portion of the latch. The recessed portion of the latch is secured on a holder 62 which is mounted on a pivot 64 and controlled by a 30 spring 66, said recessed portion being adjustable upwardly or downwardly on its holder to conform to different limits of movement of the arm 52 depending upon the extent of the movement imparted by the 35 wipers to the margin holding means.

40 This invention has been shown and described for explanatory purposes as an improvement applied to a machine used for shaping the heel portions of upper materials, including the heel stiffener and lining, preparatory to lasting. It is to be understood, 45 of course, that the invention may be applied to any machines for forming sole attaching flanges on upper materials, such as toe shaping machines, stiffener shaping machines, 50 and toe and heel lasting machines, and the term "upper" is used herein in a comprehensive sense with a view to such various uses of the invention.

Having explained the nature of this invention and described a preferred embodiment thereof, I claim as new and desire to secure by Letters Patent of the United States:—

1. In an upper shaping machine, the combination with a form, and wipers adapted to bend the margin of the work inwardly over the form to produce a sole attaching flange, of margin holding means mounted on the form and operating to hold the margin of 65 the work against the wipers.

2. In an upper shaping machine, the combination with a heel form, heel embracing wipers, and means to advance and close the wipers over the tread face of the form to bend the margin of upper materials over the 70 edge of the form and gather them into an inturned sole attaching flange, of margin holding means on the form to maintain the margin of said materials in upstanding relation to the wipers, said holding means being guided by the form to cause said means to retreat and close by movement transmitted from the wipers through said materials.

3. In an upper shaping machine, the combination with a form, and means adapted to 80 bend the margin of the work inwardly over the form, of margin holding means mounted on the form and pressed into a normal position adjacent to the edge of the form.

4. In an upper shaping machine, the combination with a form, and means adapted to 85 bend the margin of the work inwardly over the form, of margin holding means guided on the form and pressed into a normal position adjacent to the edge of the form, and 90 means for causing said margin holding means to be retained in a position remote from the edge of the form.

5. In an upper shaping machine, the combination with a form and means adapted to 95 bend the margin of the work inwardly over the form, of margin holding means arranged to extend along the margin of the work around the end of the form and movable by the bending means over the tread face of the 100 form, and means for causing said margin holding means to be retained in the position to which it is so moved.

6. In an upper shaping machine, the combination with a shoe form and means adapted to 105 bend the margin of the work inwardly over the form, of margin holding means spring pressed toward the end of the form and movable inwardly by the bending means, and means for controlling the 110 margin holding means to prevent return movement thereof with the bending means.

7. In an upper shaping machine, the combination with a shoe end form, and end embracing wipers arranged to advance and 115 close for bending the margin of the work over the form to produce a sole attaching flange, of members jointed together and yielding held in relation to present an outer margin holding face with its lower 120 edge adjacent to the edge of the form while permitting relative collapsing and bodily movement transmitted from the advancing and closing wipers, and means to prevent return of said members from the position to 125 which the wipers move them.

8. In an upper shaping machine, the combination with a form and flange bending means movable over the form, of a guide-way in the form, and work margin holding 130

means movable in the guideway by force transmitted through the work by the bending means.

9. In an upper shaping machine, the combination with a form and flange bending means movable over the form, of a guideway in the form, a foot piece movable in the guideway, work margin holding means comprising two members pivoted together 10 and to the foot piece in position to oppose the action of the bending means, a slide rod guided in the foot piece, links connecting the free ends of said members to the adjacent end of the slide rod, and yielding means 15 acting through the slide rod to maintain said members in work margin upholding position.

10. In an upper shaping machine, the combination with a form having a curved 20 edge, and end embracing wipers to bend the margin of a piece of work over said curved edge, of margin upholding means mounted on the form and normally presenting an operative face above and adjacent to said 25 curved edge and movable by the wipers inwardly and to a reduced curvature while holding the work margin against the formation of folds therein as it is gathered inwardly across said curved edge.

30 11. In an upper shaping machine, the combination with a form and flange bending means movable over the form, of work margin holding means moving along a guideway on the form in a plane parallel 35 with the flange shaping face of the form by force transmitted thereto from the bending means.

12. In an upper shaping machine, the combination with a form having a convexly 40 curved edge to assist in shaping the portion of an upper around the end of a shoe, and flange bending means movable over the form, of work margin holding means guided in a plane parallel with the flange-shaping 45 face of the form for movement in said plane by force transmitted thereto from the bending means, and spring means tending to resist movement of said holding means to cause the holding means to maintain the 50 margin of the work upstanding around the end of the form while the bending means strips it out to produce a flange over said curved form edge.

13. An upper shaping machine having a 55 support for a form, end embracing wipers movable to bend the margin of the work inwardly over the form to produce a sole attaching flange, margin holding means for engaging the upper around the end of 60 the form, and means for preventing outward flange displacing movement of said margin holding means during a return stroke of the wipers.

14. An upper shaping machine having

a support for a form, end embracing wipers 65 movable to bend the inmargin of the work inwardly over the form to produce a sole attaching flange, margin holding means spring-pressed toward position to uphold the margin of the work against the wipers 70 as the wipers bend the margin inwardly, driving mechanism and connections organized to reciprocate the wipers repeatedly, and latching means to prevent outward movement of the margin holding means 75 over the form during a return stroke of the wipers.

15. In a shaping machine, the combination with a support for a form, of a wiper, operating mechanism arranged to reciprocate the wiper a plurality of times to bend the margin of the work over the form to produce a flange and then further to rub the flange, and means which is arranged to hold the margin of the stock against the 85 wiper during the first advance of the wiper and thereafter to be maintained in a retracted position during a succeeding reciprocation of the wiper.

16. In a shaping machine, the combination with a support for a form, a wiper, and operating mechanism organized to move the form into the field of the wiper and to move the wiper to bend the margin of the stock over the form to produce a 90 flange and then to move the wiper to rub the flange, said operating mechanism being further organized to effect a return of the form from the field of the wiper, of a margin holding means automatically operative to sustain the margin of the stock during the bending movement of the wiper, to remain in a retracted position during the rubbing of the flange and to return to position for use with the next piece of work. 100

17. In a shaping machine, the combination with a support for a form, a wiper, operating mechanism organized to move the form into the field of the wiper and to move the wiper to bend the margin of the stock 110 over the form to produce a flange and then to move the wiper to rub the flange, said operating mechanism being further organized to effect a return of the form from the field of the wiper, of a margin holding means 115 spring-pressed to position to sustain the margin of the stock during the flange bending operation, a latch to prevent return of said means during the flange rubbing operation, and means to release the latch after the 120 rubbing operation.

18. In an upper shaping machine, a form, a wiper movable over the form, and means to hold the margin of the work against the wiper during a wiper advance and subsequently to push the work from the form. 125

19. In an upper shaping machine, a form, a wiper, means to hold the margin of the

work against the wiper during a wiper advance, and actuating and controlling devices operative to prevent return of said means during a retreat of the wiper and thereafter to cause said means to push the work from the form.

20. In an upper shaping machine, a form, a wiper, and work margin holding means guided in the form and operative to hold the work against the wiper while the wiper is advanced to bend the margin into a flange and to engage the edge of the flange and push the work from the form after the wiper has disengaged the work.

21. In an upper shaping machine, the combination with a form, and wipers adapted to bend the margin of the work inwardly over the form to produce a sole attaching flange, of margin holding means constructed and operated automatically to present a margin engaging face opposite to the inner edges of the wipers and outside of the boundary of the flange shaping face of the form and to coöperate with said edges of the wipers to grip the margin before the margin is bent forwardly with relation to the form.

22. In an upper shaping machine, the combination with a form having a rear end face convex in a plane perpendicular to its tread face, and wipers adapted to bend the margin of the work inwardly over the form to produce a sole attaching flange, of margin holding means constructed and operated automatically to present a margin engaging face opposite to the inner edges of the wipers and at a distance from the boundary of said tread face substantially equal to the extent of projection of said convex end face rearwardly beyond said boundary and to coöperate with said edges of the wipers to grip the margin before the margin is bent forwardly with relation to the form.

23. In a machine for shaping the rear part of a shoe upper, the combination with a heel form, of shoe end embracing means, and means to grip the margin of the upper where it extends above the curved rear end of the form and hold it upstanding to prevent displacement of the upper during the closing of the embracing means.

24. In a machine for forming a sole attaching flange on a portion of stock adapted to extend around the heel portion of a foot, the combination with a heel form, of means constructed and arranged to grip the margin of the stock which stands up around the curved rear edge of the form and to hold it in its upstanding condition to restrain the portions of stock that extend forwardly along the sides of the form from downward displacement while the stock is being shaped.

25. In an upper shaping machine, a shoe form having a guideway extending along its tread face, means movable inwardly over

said face to shape the margin of an upper into an inwardly projecting flange, and means for holding the margin of the upper against said shaping means, said holding means being movable along said guideway in response to pressure of the shaping means in its operative movement.

26. In an upper shaping machine, a shoe form having a guideway extending lengthwise thereof, wipers arranged to advance and close over the end of said form to shape the margin of the upper into an inwardly projecting flange, and means arranged to extend along the inner edges of said wipers to hold the margin of the upper upstanding against said edges, said holding means being mounted for movement along said guideway in response to the pressure of the wipers.

27. In a machine for shaping an upper over a shoe form, end embracing wipers arranged to advance and close over the tread face of the form, means for holding the margin of the upper upstanding against the edges of said wipers comprising members arranged to extend along said edges and relatively movable as the wipers close, and spring means arranged to force said holding means lengthwise of the form toward the edges of the wipers while permitting said holding means to yield in response to the pressure of the wipers.

28. In a machine for shaping an upper over a shoe form, end embracing wipers arranged to advance and close over the tread face of the form, means for holding the margin of the upper upstanding against the edges of said wipers comprising members arranged to extend along said edges and pivoted together for relative movement as the wipers close, toggle links connected to said members, and spring means arranged to operate through said toggle links and tending to resist movement of said members in response to the pressure of the wipers.

29. In a machine for shaping an upper over a shoe form, means movable inwardly over said form to shape the margin of the upper stock into an inwardly projecting flange, means extending along the margin of the upper around the end of said form for engaging said margin and holding it against the shaping means, said holding means being movable inwardly with the shaping means against yielding resistance, and means for preventing outward return movement of the holding means with the shaping means.

30. In a machine for shaping an upper over a shoe form, means movable inwardly over the end of said form to shape the margin of the upper into an inwardly projecting flange, margin holding means movable backwardly from the end of the form as said shaping means advances, spring means against the tension of which said holding

means is backwardly movable, and means for preventing return movement of said holding means with the shaping means.

31. In a machine for shaping stock over a form, bending means movable over the form to shape the margin of the stock into an inwardly projecting flange, power driven mechanism automatically operative to reciprocate said bending means a plurality of 5 times over the form to bend the margin inward and to rub it down, means for holding the margin of the stock against said bending means in the first inward movement of said means, said holding means being arranged to be forced inward over the form by the bending means, and means for preventing outward return movement of the holding means during further reciprocatory movement of the bending means.

32. In a machine for shaping an upper over a shoe form, end embracing wipers arranged to advance and close over the tread face of the form, mechanism for imparting a plurality of reciprocatory movements to said wipers, means for holding the margin of the upper upstanding against the edges of said wipers in their first inward movement, said holding means being arranged to be forced inward against yielding resistance by the wipers, and a retaining device for preventing outward return movement of said holding means during further reciprocatory movement of the wipers.

33. In a machine for shaping stock over a form, bending means movable inwardly over the form to shape the margin of the stock into an inwardly projecting flange, said bending means being movable from an initial position outside of the boundary of the flange shaping face of the form inwardly over said face, and means for holding the margin of the stock upstanding against said bending means as said means moves inwardly, said holding means also being arranged to occupy an initial position in which its stock engaging face is outside of the boundary of the flange shaping face of the form.

34. In an upper shaping machine, the combination with a shoe form presenting a rear end face convexly curved heightwise of the shoe, of end embracing wipers for gathering and wiping the margin of an upper inwardly over the heel seat face of said form, members mounted for movement lengthwise and laterally of the form in response to pressure of the wipers and presenting upper engaging faces transverse to the plane of the wipers and in front of the wiper edges to cooperate with said edges to grip the margin 60 of the upper as it is wiped inwardly, and

spring means for positioning said members initially with their upper engaging faces outside of the boundary edge of the heel seat face of the form for gripping the upper before the wipers are moved across said edge. 65

35. In a machine for shaping the end of a shoe upper, the combination with a shoe end form and end wipers adapted to advance over the bottom face of said form to bend the marginal portion of the upper inwardly 70 over said face, of a margin holding device guided on said face for movement longitudinally thereof, a pivoted spring pressed bell crank lever having one arm operatively related to said margin holding device to 75 cause said device yieldingly to maintain the margin of the upper in upstanding relation to the advancing wipers, said lever being movable about its pivot in response to said wiper advance, and a swinging spring- 80 pressed latch positioned to coöperate with and latch the other arm of said lever when moved responsively to advance of the wipers.

36. In a machine of the class described, the combination with a shoe form and end 85 embracing wipers movable to wipe the margin of an upper inwardly over the bottom face of said form, of a device movable inwardly over said face in holding engagement with the margin of the upper as the 90 wipers advance, yielding means tending to resist the inward movement of said margin holding device and comprising a bell crank having one arm arranged in operative relation to said device, and a yieldable latch 95 into operative relation to which the other arm of said bell crank is moved to restrain said yielding means from forcing the margin holding device outwardly.

37. In a machine for shaping an upper over a shoe form, the combination with means movable inwardly over the bottom face of said form to shape the margin of the upper over said face, of a device for holding the margin of the upper in engagement with said shaping means in the inward movement of said means, said device being movable inwardly over the bottom face of said form against yielding resistance in response to the inwardly directed pressure of said shaping means, and latch mechanism automatically operative to prevent return of said margin holding device from its inner limit of movement during return of the upper shaping means, said latch mechanism being 105 determinately adjustable to conform to different limits of inward movement of the device.

In testimony whereof I have signed my name to this specification.

MATTHIAS BROCK.

It is hereby certified that in Letters Patent No. 1,361,960, granted December 14, 1920, upon the application of Matthias Brock, of Boston, Massachusetts, for an improvement in "Upper-Shaping Machines," an error appears in the printed specification requiring correction as follows: Page 5, line 33, claim 11, for the word "moving" read *movable*; and that the said Letters Patent should be read with this correction therein that the same may conform to the record of the case in the Patent Office.

Signed and sealed this 1st day of March, A. D., 1921.

[SEAL.]

L. B. MANN,

Acting Commissioner of Patents.

Cl. 12—14.
